United States Patent

Des. 237,687
Patented Nov. 18, 1975

237,687

FOOD CONTAINER PACKAGE

Daniel Bernhardt, Palisade, N.J.
(406 N. Midland Ave., Saddle Brook, N.J. 07662)

Filed June 7, 1974, Ser. No. 477,450

Term of patent 14 years

Int. Cl. D9—03

U.S. Cl. D9—192

FIG. 1 is a top plan view of a food container package showing my new design;

FIG. 2 is a side elevational view thereof;

FIG. 3 is an end elevational view thereof;

FIG. 4 is an end elevational view thereof taken from the direction opposite to that of FIG. 3;

FIG. 5 is a bottom plan view thereof.

I claim:

The ornamental design for a food container package, substantially as shown.
